DESIGN FOR A TEA KETTLE

Dave Chapman, Chicago, Ill., assignor to Club Aluminum Products Co., Chicago, Ill., a corporation of Delaware

Application June 10, 1946, Serial No. 130,587

Term of patent 14 years

(Cl. D44—25)

To all whom it may concern:

Be it known that I, Dave Chapman, a citizen of the United States and a resident of Chicago, county of Cook, and State of Illinois, have invented a new, original, and ornamental Design for a Tea Kettle, of which the following is a specification, reference being had to the accompanying drawing, forming a part thereof, in which

Fig. 1 is a perspective view of a tea kettle showing my new design, and Fig. 2 is a top plan view of the same.

I claim:

The ornamental design for a tea kettle, substantially as shown.

DAVE CHAPMAN.
